US00D502638S

(12) **United States Design Patent** (10) Patent No.: **US D502,638 S**
 Winig et al. (45) Date of Patent: **** Mar. 8, 2005**

(54) **TOOL SPINDLE**

(75) Inventors: **Alan Winig**, Wynnewood, PA (US);
Richard Winig, Villanova, PA (US);
James Eldon, Barto, PA (US); **Lea**
Bogdan, Philadelphia, PA (US)

(73) Assignee: **SS3 Storage Systems, LLC**,
 Wilmington, DE (US)

(**) Term: **14 Years**

(21) Appl. No.: **29/192,165**

(22) Filed: **Oct. 20, 2003**

(51) LOC (7) Cl. **08-05**

(52) U.S. Cl. **D8/71; D8/356**

(57) **CLAIM**

The ornamental design for a tool spindle, as shown and described.

DESCRIPTION

FIG. 1 is a front perspective view of the tool spindle according to the invention;

FIG. 2 is a top view of the tool spindle;

FIG. 3 is a side view of the tool spindle; and,

FIG. 4 is an end view of the tool spindle.

1 Claim, 2 Drawing Sheets
